BASIC ESTERS OF ALIPHATIC TERTIARY
CARBOXYLIC ACIDS

Henry Martin and Alfred Margot, Basel, Switzerland, assignors to J. R. Geigy A. G., Basel, Switzerland, a Swiss firm

No. Drawing. Application August 14, 1944, Serial
No. 549,492. In Switzerland August 4, 1943.

5 Claims. (Cl. 260—293)

1

Heretofore only basic substituted esters of hydroxy acids, such as for example of tropic acid, of amygdalic acid, of atroglyceric acid, of benzilic acid, of o- and m-hydroxybenzoic acid or corresponding derivatives of benzoic acid, of phenyl acetic acids and of their hydrogenation products, have become known as compounds having neurotropic, atropine-like properties.

According to experiments of Fromherz and of other authors (cf. Arch. exp. Path. u. Pharm. 173, 124 (1933)) basic esters of aliphatic carboxylic acids do not possess antispasmodic effects in any great extent. The aliphatic carboxylic acid esters known by the patent literature, such as the isovaleric acid ester, the α -bromoisovaleric acid ester, the isopropylallyl acetic acid ester, the diethyl acetic acid ester of the 3-diethylamino-2:2-dimethyl-1-propanol, also show only a very small neurotropic-atropine-like behaviour. Moreover, the esters mentioned by Halpern (cf. Arch. internat. de Pharmacodyn., 59, 149 (1938)), such as the ethylbutyl acetic acid ester or the dibutyl acetic acid ester of diethylaminoethanol, the dibutyl acetic acid ester of diethylamino-(1)-propanol-(3), the acetic acid ester, propionic acid ester, n-butyric acid ester, diethyl acetic acid ester, ethylbutyl acetic acid ester or the dibutyl acetic acid ester of diethylamino-(1)-pentanol-(4), do not have much better effects.

It has now been found that the basic esters of aliphatic tertiary carboxylic acids possess a manifest neurotropic, atropine-like efficacy and, in addition, besides good papaverine-like properties. When applying these products the mostly undesired by-effects of atropine are largely diminished or even avoided.

For the preparation of the esters for instance reactive derivatives of the aliphatic tertiary carboxylic acids, i. e. their halides, esters or anhydrides, are caused to react in the presence or absence of condensation agents with tertiary substituted amino alcohols or reactive esters of the said amino alcohols are interacted with the above-mentioned acids or their salts, if necessary in the presence of acid binding agents.

As aliphatic tertiary carboxylic acids, there may be used compounds of the type

2

R, R' and R'' meaning the same or different saturated or unsaturated alkyl radicals.

The tertiary trialkyl acetic acids which are used as starting material may be obtained by alkylating the nitriles of mono- or dialkyl acetonitriles in the presence of sodium amide according to Ziegler, Annalen der Chemie, vol. 495, page 84 or German Patent 570,594 and subsequent hydrolysis of the so-obtained nitriles with an alcoholic solution of sodium or potassium hydroxide at temperatures ranging up to 180° C.

Reactive esters of amino alcohols falling within the scope of the invention are especially esters with hydrogen halide acids, with aryl sulfonic acids and the like.

A further object of the invention consists in converting aliphatic tertiary carboxylic acids into their halogen alkyl esters and in causing the latter to react with secondary amines. For the preparation of halogen alkyl esters, it is advantageous to react alkylene halogen hydrides with aliphatic tertiary carboxylic acids or with their halides, esters or anhydrides in the presence or absence of condensation agents or to react alkylene halogen hydrides or alkylene dihalides with salts of the said acids, the hydroxyl groups which may be present in the so-obtained compounds being subsequently replaced by halogen.

The basic esters claimed herein are colorless oils which, in form of their salts with inorganic or organic acids, are soluble in water.

The present invention will now be illustrated by way of the following examples, the parts being by weight, unless otherwise stated.

35 Example 1

9 parts of methyl-di-n-propyl acetic acid chloride are added, while stirring, to 6 parts of diethyl-amino ethanol and the mixture is heated, under stirring, for a short time to 180° C. The clear, yellowish-brown solution is treated, advantageously still warm, with water and the aqueous solution is extracted several times with ether. Then the base is freed by means of concentrated ammonia and extracted with ether. After having once washed the ethereal solution with water and then having dried the same, the solvent is distilled off. The residue boils at 133° to 136° C. when distilled at a pressure of 11 mm.

When using, instead of the diethylamino eth-

3

anol, other basic alcohols, for instance the following esters having the boiling points mentioned below are obtained:

esters of the methyl-di-n-propyl acetic acid with	boiling point at	mm.
dimethylamino ethanol	° C.	
dimethylamino propanol	115-118	11
diethylamino propanol	129-132	11
piperidino ethanol	147-150	11
piperidino propanol	155-157	11
n-dimethylamino cyclohexanol	168-174	11
	148-152	0.1

The piperidino ethanol ester of methyl-di-n-propyl acetic acid forms a hydrochloride of the melting point of 153°-155° C.

Example 2

16 parts of methyl ethyl-*n*-butyl acetic acid are heated for 24 hours to boiling, while stirring, with 14 parts of β -chloroethyl diethylamine and with 20 parts of potassium carbonate in 250 parts by volume of dry acetic acid ester. After cooling the potassium chloride is filtered by suction, the residue is washed with acetic acid ester and the combined acetic acid ester solutions are treated with dilute hydrochloric acid. The resulting acid solution is extracted with ether, then the base is freed by addition of a potassium carbonate solution and extracted with ether. After drying of the ethereal solution the solvent is distilled off. The residue boils at 11 mm. pressure at 137°-139° C.

In an analogous manner for instance the following esters are obtained with the corresponding acids:

diethylamino ethanol ester of the	boiling point at—	mm.
	°C.	
ethyl-di-n-propyl acetic acid	143-145	11
methyl-di-isobutyl acetic acid	150-151	11
methyl-n-propyl-n-butyl acetic acid	147-148	12
dimethyl-n-amyl acetic acid	129-132	11
dimethyl-n-propyl acetic acid	115-117	11
diethyl-allyl acetic acid	132-137	11
methyl-n-butyl-isobutyl acetic acid	150-153	11
ethylidene-n-butyl acetic acid	139-142	11
diethyl-n-butyl acetic acid	106-107	0.2

Example 3

35 parts of diethyl-n-butyl acetic acid chloride are caused to react in the presence of pyridine with 17 parts of ethylene chlorohydrine. After complete reaction the mixture is extracted with ether and water, the ethereal solution is dried and the solvent distilled off. The residue is fractionated in vacuo and 20 parts of the so-obtained diethyl-n-butyl acetic acid- β -chloroethyl ester are interacted in the heat with 14 parts of piperidine. The mixture is extracted with ether and water. After having dried the ethereal solution the solvent is distilled off. The residue boils at 11 mm. pressure at 146°-149° C.

When using the corresponding acid chlorides, there may be obtained for instance the following esters:

piperidino ethanol ester of the	boiling point at—	mm.
methyl-di-isobutyl acetic acid.....	°C 172-174	12
methyl-n-butyl-isobutyl acetic acid.....	170-172	12
methyl-n-propyl-n-butyl acetic acid.....	165-167	11

Example 4

10 parts of methyl-di-isobutyl acetic acid chloride are brought to interaction with 5 parts of dimethylamino propanol and worked up in the manner described in Example 1. Thus the dimethylaminopropanol ester of the methyl-di-isobutyl acetic acid is obtained in form of a colorless oil having the boiling point at 13 mm. pressure of 146°-149° C.

10 When using methyl-n-propyl-n-butyl acetic acid chloride and diethylamino propanol, there will be obtained in an analogous manner the corresponding ester boiling at 12 mm. pressure at 160°-162°; from methyl ethyl-n-butyl acetic acid chloride and m-methylethylamino cyclohexanol the corresponding ester of the boiling point at 0.1 mm. pressure of 162°-165° C. is obtained, while by interaction of ethylidene-n-butyl acetic acid chloride and dimethyl amino propanol the corresponding ester boiling at 11 mm. pressure at 138°-140° C. will be produced.

What we claim is:

1. A basic ester of an aliphatic tertiary carboxylic acid, of the formula

30 wherein A₁ and A₂ each represents a lower alkyl group and A₁ and A₂ together contain from 5 to 8 carbon atoms, X represents a divalent radical selected from the group consisting of $-\text{CH}_2\text{CH}_2-$, $-\text{CH}_2\text{CH}_2\text{CH}_2-$ and

40 radicals, and Am stands for the radical of a secondary amine selected from the group consisting of lower dialkyl amines and piperidine.

2. A basic ester of an aliphatic tertiary carboxylic acid, of the formula

50 wherein A_1 represents an alkyl radical containing at least 3 and at most 5 carbon atoms, A_2 represents an alkyl radical containing at least 2 carbon atoms, and A_1 and A_2 together contain from 5 to 8 carbon atoms, X represents a divalent radical selected from the group consisting of
55 $-\text{CH}_2\text{CH}_2-$, $-\text{CH}_2\text{CH}_2\text{CH}_2-$ and

radicals, and Am stands for the radical of a secondary amine selected from the group consisting of lower dialkyl amines and piperidine.

65 3. The piperidinoethanol ester of methyl-di-n-propyl acetic acid of the formula

being a colorless oil of the boiling point of 155°-157° C. at 11 mm. pressure and forming a hydro-

chloride of the melting point of 153°-155° C., possessing valuable therapeutic properties.

4. The dimethylaminopropanol ester of methyl-di-isobutyl acetic acid of the formula

being a colorless oil of the boiling point of 146°-149° C. at 13 mm. pressure, possessing valuable therapeutic properties.

5. The diethylaminoethanoester of methyl-n-propyl-n-butyl acetic acid of the formula

5

10

20

being a colorless oil of the boiling point of 147°-148° C. at 12 mm. pressure, possessing valuable therapeutic properties.
